DESIGN FOR AN EMBROIDERED FABRIC SCARF OR SIMILAR ARTICLE

Martin Seidel, Bogote, N. J., assignor to Record Lace & Embroidery Company, Inc., New York, N. Y., a corporation of New York

Application July 20, 1940, Serial No. 93,807

Term of patent 3½ years

To all whom it may concern:

Be it known that I, Martin Seidel, a citizen of the United States of America, residing at Bogote, in the county of Bergen and State of New Jersey, have invented a new, original, and ornamental Design for an Embroidered Fabric Scarf or Similar Article, of which the following is a specification, reference being had to the accompanying drawing, forming part thereof.

The figure on the drawing is a plan view of approximately one-half of the embroidered fabric scarf or similar article showing my new design, the other half being a repetition thereof in reverse position.

I claim:

The ornamental design for an embroidered fabric scarf or similar article, as shown and described.

MARTIN SEIDEL.
